UNITED STATES PATENT OFFICE.

ANNA M. HUNTINGTON, OF PHILADELPHIA, PENNSYLVANIA.

DESIGN FOR A PERFUMED SACHET.

SPECIFICATION forming part of Design No. 17,423, dated June 28, 1887.

Application filed May 28, 1887. Serial No. 239,703. Term of patent 3½ years.

To all whom it may concern:

Be it known that I, ANNA M. HUNTINGTON, a citizen of the United States, residing in the city and county of Philadelphia and State of Pennsylvania, have invented and produced a new and original Design for Sachets for Containing Perfumery, of which the following is a specification, reference being had to the accompanying drawings, forming part thereof.

Figure 1 is a front view, and Fig. 2 is a back view, of my newly-designed sachet, these two views being deemed necessary to fully illustrate my design.

The leading feature of my design consists in a band, A, dividing the front and back surfaces, B and C, of the sachet in quarters, said

tie A terminating in an ornamental bow, D, on the back C of the sachet, a seal, E, placed on the tie A, and the pictured floral decoration F upon the back surface, C, of the sachet, as shown in Fig. 2 of the drawings.

I claim—

The design for a perfumed sachet herein shown and described, the same consisting of the band A, dividing the front and back surfaces in quarters, the ornamental bow D, seal E, and pictured floral decoration F, as shown and described.

ANNA M. HUNTINGTON.
